H. LIEBECK

STEAM DRYING SYSTEM FOR PAPER MAKING AND OTHER MACHINES

Filed May 15, 1922

Patented June 5, 1923.

1,457,779

UNITED STATES PATENT OFFICE.

HARRY LIEBECK, OF SWARTHMORE, PENNSYLVANIA, ASSIGNOR TO SCOTT PAPER COMPANY, A CORPORATION OF PENNSYLVANIA.

STEAM-DRYING SYSTEM FOR PAPER-MAKING AND OTHER MACHINES.

Application filed May 15, 1922. Serial No. 560,938.

To all whom it may concern:

Be it known that I, HARRY LIEBECK, a citizen of the United States, and resident of Swarthmore, county of Delaware, and State 5 of Pennsylvania, have invented an Improvement in Steam-Drying Systems for Paper-Making and Other Machines, of which the following is a specification.

It has been customary in connection with 10 paper making machines and in the textile industry to provide a large number of steam heated drying cylinders about which the paper or fabric is caused to pass and which, by reason of contact with the revolving drying 15 cylinders, are brought to a dry condition.

In drying apparatus of this character, it has been customary to group the drying cylinders into a series of sections and supplying steam thereto in such manner that the 20 steam which passes through the drying cylinders of the first section (which may be designated as the "dry" end) is supplied to the drying cylinders of the next section and so on through the successive sections until 25 the last or "wet" end section is heated. The water of condensation has been collected from the return mains of the various sections and thereby removed from the circulation. It has further been customary, 30 where the steam in any section is insufficient for requirements, to by-pass a part of the steam from the supply pipe of the previous section, whereby a greater supply of steam may be had than what would have been the 35 case if the steam from the return mains of the previous section had alone been depended upon for the steam supply.

I have found that, especially in connection with the making of paper and paper board, 40 these drying systems, as heretofore constructed and used, are not as flexible in respect to the steam circulation and control as they should be to meet the special requirements which are from time to time occurring, and it is the object of my invention to so modify the general systems heretofore employed so as to secure the requisite flexibility and efficiency which I deem desirable and practically essential to secure the best 50 results with a limited number of drying cylinders and normally available steam supply.

In putting my invention into practice, I arrange the drying cylinders in groups to constitute a series of sections, each contain-

ing the number of cylinders which is predetermined by the grade of paper or material to be treated, and combine with the said drying cylinders a system of supply and return pipes communicating with the cylinders, and furthermore, provided with valves and by-pass pipe connections also provided with valves, whereby the number of sections may be varied by manipulation of the valves so that all of the cylinders may be grouped as one section, or for operation, in any other combination up to the full number of sections for which it is normally designed. Such capacity for regrouping the various drying cylinders permits the system to be so operated that one steam pressure may be 55 simultaneously employed in all of the drying cylinders or, by special manipulation of the valves involving the closing of some and opening of others, steam of various pressures and temperatures may be introduced 60 into consecutive sections of the driers. 70

My invention further comprehends, in connection with the above control of the steam supply, of a system of water drainage whereby the accumulations of water of condensation from the various sections may be 80 automatically removed.

With the above and other objects in view, the nature of which will be more fully understood from the description hereinafter, 85 the invention consists in the novel construction of steam drying systems for paper making and other machines, as hereinafter more fully described and defined in the claims.

Referring to the drawings: Fig. 1 is a diagrammatic side elevation of a drying apparatus embodying my improved system of cylinder and pipe connections, and associated means for removing the water of condensation; and Fig. 2 is a side elevation of one of the drying cylinders in connection with its journal support and association with supply and return mains which latter are shown in section.

For convenience, I have indicated the drying cylinders as arranged in four sections, those of section 1 being numbered 2, those of section 2 being numbered 3, and similarly, those of sections 3 and 4 being numbered 105 respectively 4 and 5. The steam supply main is indicated by the sections 6, 7, 8, 9 and 10, which may be separated by shut-

off valves 13, 14, 15 and 16. Valve 13 is the main steam supply valve. From the steam supply pipe 7 steam is supplied to the drying cylinders 2 of section 1 by upright steam pipes 12. In the case of section 2, similar steam pipes 12 connect the supply main 8 with the drying cylinders 3. In the same manner the supply pipes 9 and 10 supply steam to the drying cylinders 4 of section 3 and cylinders 5 of section 4.

The return main is divided into sections 17, 18, 19 and 20 by the presence of the shut-off valves 22, 23 and 24. The return main 17 corresponds to section 1 and receives the water of condensation and escaping steam through pipes 21 from the drying cylinders 2 thereof. Similarly, the return main 18 corresponding to section 2 receives the water of condensation and steam from the drying cylinders 3 thereof by corresponding pipes 21. In the same manner, the return mains 19 and 20 corresponding to sections 3 and 4 respectively receive the steam and water of condensation through similar pipes 21 from their respective drying cylinders 4 and 5. It is to be understood, however, that in an efficient operation of the system, the steam received in the drying cylinders 5 of section 4, constituting the "wet" end of the system, is intended to be substantially condensed, so that the return main 20 mainly receives water of condensation since there is no requirement for further transmission of steam beyond section 4.

In addition to the steam supply mains and return mains, I provide a series of by-passes 25, 27 and 29 connecting the steam supply mains and return mains in the manner illustrated and these by-passes are respectively provided with control valves 26, 28 and 30. As will be seen from the drawing, the by-pass 25 connects the return main 17 of section 1 with the supply main 8 of section 2. Similarly, the by-pass pipe 27 connects the return main 18 of section 2 with the supply main 9 of section 3. Also return main 19 of section 3 connects through by-pass pipe 29 with the supply main 10 of section 4. The pressure in the various pipes or portions of the system may be readily read from gages 41 on a gage board 40 suitably located and wherein said gages are connected by piping indicated at 42, respectively communicating with the supply main 7 of section 1 and the return mains 17, 18, 19 and 20 of the respective sections 1, 2, 3 and 4.

In addition to the steam supply system above described, the apparatus is provided with the following construction for removing the water of condensation to prevent water logging of the system. The water of condensation from the return main 17 is conveyed downwardly by a pipe 31 to a trap 32 and thereby discharged into a water return main 39, which may lead to the sewer

or act as a water return pipe to deliver the water of condensation to a tank from which it may be delivered to the boiler. The return main 18 is provided with a water return pipe 33 leading to a trap 34 which likewise discharges into the water return main 39. Similarly, the return main 19 delivers its water of condensation through pipe 35 and trap 36 into the water return main 39; and likewise, return main 20 delivers its water of condensation through pipe 37 and trap 38 into the water return main 39. As shown in the drawing, the traps 32, 34, 36 and 38 are indicated as tilting traps but may be of any suitable construction, as I in no wise limit myself in this respect. In case of the traps 32, 34 and 36, they should be of a construction wherein the water may be freely removed while preventing the escape of steam. In the case of trap 38 in connection with section 4, there would be practically no steam passing by pipe 37 to the trap where the sections are operated independently in series, but in such case as where all of the sections are operated as one section by the closing of the valves 26, 28 and 30, and opening all of the valves 14, 15, 16, 22, 23 and 24, the trap 38 should operate as in the case of the other traps and, therefore, it would be desirable that all of the traps shall be of a similar construction, though I do not restrict myself in this particular.

Assuming the operation of this system to be such that the various sections 1, 2, 3 and 4 are operated in series, then and in that event, valves 14, 15, 16, 22, 23 and 24 are closed and valves 26, 28 and 30 are opened. Steam from main 6 is admitted to supply main 7 by valve 13, and the water of condensation as well as the uncondensed steam passing from the drying cylinders 2 are delivered to the return main 17. The water of condensation is drained off by a pipe 31 and delivered by trap 32 to the water return main 39. The steam from the return main 17 passes upward through the by-pass pipe 25 into the supply main 8 of section 2. The water of condensation and uncondensed steam passing from the cylinders 3 of section 2 are then delivered into the return main 18, from which the water of condensation is removed by pipe 33 and trap 34, and the steam is conveyed by upright by-pass pipe 27 to the supply main 9 of section 3, and thence delivered to the drying cylinders 4. Similarly, the water of condensation and steam from the drying cylinders 4 are received in return main 19 from which the water of condensation passes by pipe 35 and is delivered by trap 36 to the water return main 39 and the steam is delivered through vertical by-pass pipe 29 to the supply main 10 and thence to the drying cylinders 5 of section 4 which constitutes the "wet" end of the system. The water of condensation received from the

drying cylinders 5 into the return main 20 is delivered by pipe 37 and trap 38 into the water return main 39.

If it should be required that sections 1 and 2 be grouped as one section and sections 3 and 4 as a second section, then it will be understood that all that is necessary is that valves 14, 22, 16 and 24 be opened and valves 26 and 30 be closed. Thereupon the supply mains 7 and 8 are in immediate communication. Similarly, supply mains 9 and 10 are in communication. So also return mains 17 and 18 are in direct communication, and likewise return mains 19 and 20 are in direct communication. Under this condition, the steam passing from the drying cylinders 2 and 3 will flow through the return mains 17 and 18 and by-pass pipe 27 into the supply mains 9 and 10, and the system will, therefore, be operating as a two-section system.

It will also be understood that by merely manipulating the valves in the supply mains, return mains and by-pass pipes, any other combination of sections may be had such, for example, combining sections 1 and 2 while leaving sections 3 and 4 to operate independently or in series; also to permit sections 2 and 3 to be operated as a single section while maintaining sections 1 and 4 in condition to operate separately. In fact, any combination desired may be had by the arrangement of pipes and valves shown.

Heretofore I have described the system under the assumption that valves 14, 15 and 16 were either fully opened or fully closed, but it is to be understood that in some cases these valves may be operated to by-pass a portion of the steam from the supply main of one section into the supply main of the next section; thus, for example, if the valve 14 were slightly opened, part of the steam from the supply main 7 would pass into the supply main 8 for the second section and increase or augment the steam received therein from the return main 17 and by-pass pipe 25. The same operation for increasing the steam in the supply pipes 9 and 10 may equally be resorted to by the manipulation of the valves 15 and 16, respectively. It will be understood further, that if desired all of these valves 14, 15 and 16 may be slightly opened so that more or less of the steam from the source of supply 6 may be by-passed directly through these valves to supply an increased amount of steam where the material being treated causes a large amount of condensation of the steam in the cylinders of the respective sections.

From the foregoing explanations, it will be recognized that the improved construction of heating system herein described may be controlled and adjusted quickly to suit varying conditions which may arise and permit the greatest economy in the use of the

steam, always insuring just sufficient steam and of the desired pressures required to meet any special condition of treatment necessary. I prefer the arrangement of piping indicated and comprising the supply mains 70 in true alinement and at a higher elevation than the return mains which latter are also in direct alinement; and wherein the by-pass pipes 25 are upright pipes so that the water of condensation readily finds its way 75 to the lower part of the return mains for delivery through the traps to the water return main, thereby permitting the steam passing from one section to the next sections to be as dry as possible. 80

It will now be apparent that I have devised a novel and useful construction which embodies the features of advantage enumerated as desirable, and while I have in the present instance shown and described the preferred embodiment thereof which has been found in practice to give satisfactory and reliable results, it is to be understood that I do not restrict myself to the details, 85 as the same are susceptible of modification 90 in various particulars without departing from the spirit or scope of the invention.

Having now described my invention, what I claim as new and desire to secure by Letters Patent is:

1. In drying apparatus for paper making and other machines, the combination of a plurality of drying cylinders arranged in a plurality of groups constituting separate sections, with a continuous steam supply main 100 having communication with the drying cylinders of the several sections for supplying steam thereto, a continuous return main also in communication with the drying cylinders of the several sections for receiving the 105 water of condensation and uncondensed steam therefrom, by-pass pipes connecting the steam supply main and the return main at intervals along their lengths, said by-pass pipes provided with valves for respectively opening or closing communication 110 through them, valves in the supply main at intervals along its length for dividing it into sections corresponding to the sections of the drying cylinders, valves in the return main at intervals along its length for dividing it into sections corresponding to the sections of the drying cylinders, said valves in the supply and return mains arranged in pairs and each pair of valves controlling 115 120 said mains adjacent to but respectively on opposite sides of one of the by-passes, whereby the steam from one section of the return main corresponding to one section of the drying cylinders may pass by a by-pass pipe 125 into the section of the supply main corresponding to the next section of drying cylinders and so on, and means for removing the water of condensation from the return main.

2. The invention according to claim 1, wherein the sections of the steam supply main are all in the same substantial alinement and are above the by-pass pipes and 5 in which further the sections of the return main are also in substantial alinement to constitute a continuous main and arranged below the by-pass pipes.

3. The invention according to claim 1, 10 wherein there is a separate drain pipe from each section of the return main and an individual trap for permitting the passage of water and restricting the escape of steam for each of the said drain pipes.

4. In drying apparatus for paper making and other machines, the combination 15 of a plurality of drying cylinders arranged in a plurality of groups constituting separate sections, with a continuous steam supply 20 main having communication with the drying cylinders of the several sections for supplying steam thereto, a continuous return

main also in communication with the drying cylinders of the several sections for receiving the water of condensation and uncondensed steam therefrom, by-pass pipes connecting the steam supply main and the return main at intervals along their lengths, valves for controlling the flow of steam through the steam supply and return mains and through the by-pass pipes, whereby the sections of the drying cylinders may be coupled in various ways so that steam may be caused to circulate through them in succession or in multiple or in combinations, and whereby further, part of the sections may be coupled in multiple and said part in series with another section or section as required, and means for removing the water of condensation from the return main. 25 30 35 40

In testimony of which invention, I hereunto set my hand.

HARRY LIEBECK.
